UNITED STATES PATENT OFFICE.

SAMUEL B. SHELDON, OF DULUTH, MINNESOTA.

BOTTOM-MAKING MACHINE FOR FURNACES.

Application filed January 16, 1922. Serial No. 529,804.

To all whom it may concern:

Be it known that I, SAMUEL B. SHELDON, a citizen of the United States, residing at Duluth, in the county of St. Louis and 5 State of Minnesota, have invented certain new and useful Improvements in Bottom-Making Machines for Furnaces, of which the following is a specification.

This invention relates to a new and improved bottom making machine for furnaces and more particularly to a machine adapted to operate upon the usual charging floor tracks and to repair and remake bottoms in open hearth furnaces.

As is well known in the art, it is constantly necessary to repair and periodically necessary to renew the bottoms in open hearth furnaces. These bottoms are composed of loose material, dolomite being the material generally used, and the general practice heretofore has been to make these repairs by hand labor. This is uneconomical as to time and as to labor cost. Due to the extreme heat under which repairs are ordinarily made, labor is inefficient and it is also extremely difficult to reach all parts of the furnace and to adequately and evenly place the bottom materials. Delays are often required to permit the parts to cool sufficiently for the repairs to be made.

It is an object of the present invention to provide a machine which is adapted to operate upon the usual charging floor tracks and which is adapted to positively and accurately place bottom making material at any desired point in the furnace.

It is a further object to provide a machine which can operate regardless of the heat conditions in the furnace.

It is also an object to provide a machine which is a self-contained unit and which can be operated with a minimum of hand labor.

Other and further objects will appear as the description proceeds.

Broadly, my invention comprises a main car frame adapted to run upon the charging machine tracks of the furnace floor, this frame supporting carriages adapted to run upon the frame transversely of the tracks 50 toward and from the furnace. The machine is supported from these carriages and is a self-contained unit comprising a material depositing gun, a material hopper, a source of compressed air for operating the gun and a water-cooling system for cooling the gun. Means are provided whereby the

gun may be swung in both horizontal and vertical planes and whereby it may be rotated about its axis. The gun is preferably provided with a curved end to aid in 60 the accurate deposition of the material and to extend its scope of operation.

I consider the feature of making the structure a self-contained unit operable upon the usual charging floor tracks to be 65 a very important feature from the practical standpoint of the operation and utility of the apparatus. The machine can be utilized in a way to readily coordinate its use with the other apparatus and operations upon the 70 charging floor. Apparatus of this general character intended to be otherwise operated or not a self-contained unit would so disrupt the usual cycle of operations and impede the movement of the usual apparatus as to 75 render its use of doubtful value.

Another important feature of the invention lies in the fact that the only portion of the apparatus which actually enters the furnace is the outer end of the gun itself. 80 This portion of the gun is thoroughly water-cooled and contains no moving parts to be subjected to warp or disruption by heat.

I have illustrated a preferred embodiment 85 of my invention in the accompanying drawings, in which—

Figure 1 is a plan view of my apparatus together with a diagrammatic representation of an adjacent portion of an open hearth furnace;

Figure 2 is an elevation of the apparatus shown in Figure 1, and

Figure 3 is a view on an enlarged scale showing the main body of the apparatus.

The machine frame 5 is supported upon the wheels 6 which roll upon the tracks 7 which are the usual tracks adapted to carry the charging machines in a manner well known in the art. These wheels are driven by the electric motor 8 through gears 9. 95 Moving longitudinally of the frame 5 is the primary carriage 10 carried upon wheels 11. This carriage is moved by means of the electric motor 12 and the cable 13 operating over pulleys 14.

Moving longitudinally of the primary carriage 10 is the secondary carriage 15 supported upon wheels 16. The secondary carriage 15 is provided at its forward end with the pivot 17 and is further provided with an arcuate series of frusto-conical rollers 18 bearing upon a suitable run way. The arc

upon which these rollers are placed has as its center the pivot 17.

The top carriage 19 is connected to the pivot 17 of the secondary carriage and rests 5 upon the frusto-conical rollers 18. It is provided toward the rear with the arcuate rack 20 and the beveled gear 21 carried by the standard 22 supported from the secondary carriage coacts with the rack to rotate the 10 top carriage about the pivot. This gear 21 is operated by the hand wheel 23.

The secondary carriage is provided with the operating platform 24, adjacent this hand wheel, and upon this platform are suitable control means 25 adapted to control the movement of the main car and of the primary and secondary carriages. The top carriage is provided with the horizontal pivot 26 to which is pivoted the tilting floor 27. The rear end of this floor 27 is supported by means of the shaft 28, the lower end of which has a bearing in the top carriage. This shaft is rotatable, having a worm connection with the tilting floor, and being provided on its upper end with the operating handle 29.

Upon the tilting floor are the two bearings 30 and 31 in which is supported the dolomite gun 32, the gun being rotatable in the bearings. The gun is provided with the rack 33 with which the gear 34 coacts, this gear being supported upon the bearing 30 and being operated by hand wheel 35. The outer end of the gun is curved downwardly at 36 and, as indicated by dotted lines at 37, an additional detachable, curved portion may be secured thereto.

The outer portion of the gun is water-jacketed, water being led through hose 38 and lead 39 to the outer end of the gun and being carried back by hose 40 to tank 41. The water is circulated by the motor driven pump 42 and is cooled in radiator 43, all of these elements being supported from the 45 tilting floor.

A dolomite hopper 44 is provided which communicates with the rear end of the gun through elbow 45. The elbow 45 has a direct connection with the main body of the gun, the connection being such that the elbow remains fixed while the gun is rotated. The motor driven air compressor 46 is supported from the tilting floor and is connected to air tank 47. The air pipe 48 leads from the tank to the rear of the elbow 45 in alignment with the bore of the gun. The flow of air is controlled by valve 49.

In the operation of my apparatus, the main car is moved along the track 7 until 60 it reaches an opening into the furnace suitable for its operation. While thus moved, the primary carriage is retracted upon the main frame and the secondary carriage retracted upon the primary carriage so that 65 the gun and operating elements are in the

position indicated in broken lines in Figure 2. In this position the gun is located entirely above the main carriage.

When the gun is brought opposite the proper opening, the main carriage is moved 70 forward upon the machine frame and the secondary carriage upon the main carriage an amount sufficient to properly introduce the gun into the furnace. It will be obvious that by various adjustment of the two carriages, it will be possible to locate the end 75 of the gun at any desired point transversely of the furnace. The gun may be rotated about its own axis so as to direct by means of the curved portion, the material to any 80 desired point. This curved portion is particularly useful when working close to the opening and upon the same side of the furnace as the opening. To reach some such points, the additional curved element 37 may 85 be necessary.

The gun may be swung to the right or left in the horizontal plane by swinging the top carriage about the pivot 17. This is accomplished by the hand wheel 23. It may be 90 swung up and down in the vertical plane by tilting the tilting floor 27 about the horizontal pivot 26. It will be observed that the operating elements are largely on one side 95 of this pivot while the long projecting gun which is comparatively heavy and also carries water for cooling projects upon the opposite side of the pivot.

The entire assembly is thus approximately 100 balanced about the pivot 26 so that the operation of hand wheel 29 to tilt the floor is rendered less difficult. The dolomite in the hopper flows by gravity to the elbow 45 and adjustment of the valve 49, which controls 105 the entrance of air into the gun, serves to regulate the deposition of the material.

My floor making machine is thus capable 110 of quickly and accurately depositing floor making material upon any portion of the floor and is adapted for rapid operation and easy control. It is operated from and carried upon the charging machine tracks and may be used from the tracks without disrupting the usual series of operations carried out upon the charging floor. Its use 115 may be readily worked into the series of such operations with a considerable speeding up in work and reduction in cost. I am aware that various modifications may be made to adapt the machine to particular 120 uses and to varying conditions. It is my intentions to cover all modifications coming within the scope of the appended claims.

I claim:

1. A bottom making machine for furnaces comprising a car structure adapted to run upon charging machine tracks upon a furnace charging floor, a carriage movable relative to said car toward and from the furnace, and a dolomite gun supported from said car. 125 130

riage and adapted for vertical and horizontal adjustment relative to the carriage.

2. A bottom making machine for furnaces comprising a car structure adapted to run upon charging machine tracks upon a furnace charging floor, a carriage movable relative to said car toward and from the furnace, and a dolomite gun supported from said carriage and adapted for vertical and horizontal adjustment relative to the carriage the gun having a curved end portion and being further provided with means adapted to rotate the gun about its axis.

3. A bottom making machine for furnaces comprising a car structure adapted to run upon charging machine tracks upon a furnace charging floor, a carriage movable relative to said car toward and from the furnace, a top carriage supported from said carriage and adapted for rotary movement relative to the carriage, and a dolomite gun supported by said top carriage.

4. A bottom making machine for furnaces comprising a car structure adapted to run upon charging machine tracks upon a furnace charging floor, a carriage movable relative to said car toward and from the furnace,

a top carriage supported from said carriage and adapted for rotary movement relative to the carriage, a horizontal pivot on the top carriage, a tilting floor carried by the top carriage and adapted to be tilted about the horizontal pivot up on the top carriage, and a dolomite gun supported upon the tilting floor.

5. A bottom making machine for furnaces comprising a car structure adapted to run upon charging machine tracks upon a furnace charging floor, a carriage movable relative to said car toward and from the furnace, a top carriage supported from said carriage and adapted for rotary movement relative to the carriage, a horizontal pivot on the top carriage, a tilting floor carried by the top carriage and adapted to be tilted about the horizontal pivot upon the top carriage, and a dolomite gun, a dolomite hopper connected thereto, a source of compressed air for operating the gun, and a source of cooling water for said gun supported upon the tilt-
ing floor.

Signed at Duluth, Minnesota, this 9th day of January, 1922.

SAMUEL B. SHELDON.
